CLAIM

The ornamental design for a door protector for automobiles, as shown and described.

DESCRIPTION

FIG. 1 is a perspective view of the door protector for automobiles;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a cross-sectional view thereof, wherein the section cutting plane is taken along 7-7 in FIG. 2; and,

FIG. 8 is a cross-sectional view thereof, wherein the section cutting plane is taken along 8-8 in FIG. 2.

The broken lines shown in the drawings illustrate portions of the door protector for automobiles that forms no part of claimed design.
